UNITED STATES PATENT OFFICE.

RISDON DENT MOORE, OF ARDMORE, OKLAHOMA.

BLINDER.

1,173,602.

Specification of Letters Patent. Patented Feb. 29, 1916.

Application filed June 28, 1915. Serial No. 36,807.

To all whom it may concern:

Be it known that I, RISDON D. MOORE, a citizen of the United States, residing at Ardmore, in the county of Carter and State of Oklahoma, have invented a new and useful Blinder, of which the following is a specification.

The device forming the subject matter of this application is adapted to be employed 10 for connecting a blinder detachably with a head stall, it being a matter of common knowledge that different conditions as to light or darkness, the nature or disposition of the animal being driven, and many other 15 considerations frequently make the attachment of blinders to a head stall and the detachment of blinders therefrom necessary.

The invention aims to provide a novel 20 means whereby, without causing excessive mutilations either in the blinder or the head stall, and without rendering either of these elements objectionable as to appearance, the blinder may be attached readily to a head stall and with equal facility be detached 25 therefrom.

It is within the province of the disclosure to improve generally and to enhance the utility of devices of that type to which the present invention appertains.

30 With the above and other objects in view which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing from the spirit of the invention.

40 In the accompanying drawing: Figure 1 shows the invention in side elevation; Fig. 2 is a section on the line 2—2 of Fig. 1; Fig. 3 shows the invention in side elevation; Fig. 4 is a fragmental plan, wherein parts are 45 broken away; Fig. 5 is a fragmental section showing a modification.

In the accompanying drawings, the numeral 1 indicates the cheek strap of a head stall, the numeral 2 denoting the head 50 strap these parts frequently being connected by means of a buckle 3. The blinder is shown at 4 and the blinder stay appears at 5, all these parts being common and well known in the art, saving as hereinafter 55 modified.

Mounted upon the cheek strap 1 is a box-

like casing 6 which may be held in place by means of rivets 7 or other securing elements, the casing 6 being provided within its contour with projections 8 which may 60 be rivets. Mounted on the outer face of the casing 6 is an eye 9 through which the end of the head strap 2 may be thrust. In the side walls of the casing 6 opposed openings 10 and 11 are fashioned.

65 The binder 4 preferably comprises co-operating parts or layers 12 united preferably by means of stitching 14 or otherwise. Between the parts 12 of the binder 4 is a resilient locking member 15 of U-shape 70 and comprising arms 18. The resilient U-shaped locking member is held in place between the parts 12 of the binder by means of stitchings 16. It is to be observed that the stitching indicated at 16 terminates at a 75 distance from the inner edge 17 of the binder 4, to the end that the arms 18 of the resilient locking member 15 may be pressed toward each other, these arms normally tending to expand and to move away from 80 each other, the blinder, as clearly shown in Fig. 2, being hollow, so as to permit the hereinbefore mentioned movement of the arms 18 toward and away from each other.

85 The arms 18 of the resilient U-shaped locking member 15 pass through the openings 10 in the casing 6 and through the openings 11 therein, the arms being provided intermediate their ends with seats 19 which coact with the projections 8. The 90 extremities of the arms 18 project beyond the rear edge of the casing 6 so as to form finger pieces 20.

In practical operation, referring particularly to Fig. 4, it will be observed that the 95 arms 18 may be pinched together by means of the finger pieces 20 and thus the seats 19 may be disengaged from the projections 8. Thereupon the arms 18 may be pulled out of the casing 6, the blinder 4 thus being detached from the head stall by a simple operation, and without the use of tools.

100 In Fig. 5, a slight modification of the invention is shown. One wall of the casing on the cheek strap is shown at 21 and an opening 22 appears therein, the same corresponding to one of the openings 11 of Fig. 4.

105 The numeral 23 designates one of the spring arms of the locking member, the same having a seat 24, the finger piece appearing at 25. In this form of the invention, the projections 8 of Fig. 4 are dis-

pensed with, the seat 24 in the arm 23 being received, as shown at 26 by the wall 21 of the casing, at the edge of the opening 22. The part 26 of the casing, therefore, like the element 8 of Fig. 4 may be described as a projection on the head stall, wherewith the spring arm of the locking member is adapted to engage.

Having thus described the invention, what is claimed is:—

1. In a device of the class described, a blinder; a pair of spring arms carried by the blinder and projecting in approximate parallelism beyond one edge of the blinder, the arms being located in a plane approximately parallel to the plane defined by the blinder, the arms being yieldable toward and away from each other, in a plane approximately parallel to the plane defined by the blinder; and head stall carried means wherewith the projecting portions of the arms are detachably interlocked.
2. In a device of the class described, a head stall having projections; a blinder; and compressible spring arms on the blinder, the spring arms being detachably

interengaged with the projections and being extended to the rear of the head stall to form finger pieces.

3. In a device of the class described, a head stall having projections; a blinder; and compressible spring arms on the blinder, the arms having seats receiving the projections, the arms being extended beyond the projections to form finger pieces whereby the arms may be compressed.

4. In a device of the class described, a blinder; a U-shaped resilient member assembled with the blinder and comprising arms, the arms adjacent their ends being mounted to move toward and away from each other, within the contour of the blinder; a head stall; and means on the head stall wherewith the arms interengage detachably.

In testimony that I claim the foregoing as my own, I have hereto affixed my signature in the presence of two witnesses.

RISDON DENT MOORE.
